[57] CLAIM

The ornamental design for a combined perfume bottle and stopper, as shown and described.

DESCRIPTION

FIG. 1 is a perspective view of the combined perfume bottle and stopper;

FIG. 2 is a front elevation thereof, the rear elevation being a mirror image of FIG. 2;

FIG. 3 is a side elevation thereof, when taken from either the left hand side or the right hand side of FIG. 1;

FIG. 4 is a top plan view thereof; and,

FIG. 5 is an underside plan view thereof.
